UNITED STATES PATENT OFFICE.

CASPER THEODOR BUCHER, OF TIFFIN, OHIO.

FILTER.

1,260,751.

Specification of Letters Patent. Patented Mar. 26, 1918.

Application filed April 28, 1916. Serial No. 94,098.

To all whom it may concern:

Be it known that I, CASPER T. BUCHER, a citizen of the United States, and resident of Tiffin, in the county of Seneca, and State 5 of Ohio, have invented certain new and useful Improvements in Filters, of which the following is a specification.

My invention relates to filters, and more particularly to that class of filters adapted 10 for location in a pipe line leading to a cistern or other receptacle for straining or filtering the water passing therethrough.

Filters of this class in most general use comprise a casing having an inlet passage 15 and two outlet passages, one of which latter leads to a cistern or like receptacle and has a filtering screen disposed across the same, while the other outlet passage leads to a waste or other pipe. A valve or like device 20 within the casing is adjustable to deflect the water through either of the said outlet passages as may be desired. In the use of filters of this class, more or less trouble is caused by reason of the "floatings" or 25 other foreign material in the water accumulating on the screen and closing the openings of the same to such an extent as to substantially shut off the flow of the water to the cistern and cause a deflection of 30 the same to the waste outlet. Having in mind this objectionable feature incident to the use of many filters now in use, it has been the main object of my present invention to provide an improved filter of the 35 type referred to, in which the filter screen will be kept free of the floatings or other foreign material in the water and thereby constantly maintained in a condition to properly perform its normal function. This, 40 and other objects and advantages to be referred to during the course of the detailed description of the invention which follows, are attained by means of my improved filter as illustrated in the accompanying drawings, in which—

Figure 1 is a side elevation of the filter, with the contained parts shown by broken and dotted lines,

Fig. 2 is a section of the same taken on 50 line 2—2 of Fig. 1, and

Fig. 3 is a side view of a spout forming part of the filter, removed from its position within the casing of the filter.

Similar reference characters indicate like 55 parts on the several figures of the drawings.

The main casing, indicated at 2, is provided with an inlet pipe 3, and two outlet pipes, 4 and 5, the pipe 4 being adapted to direct the water through a suitable conduit to a cistern or other receptacle, and the pipe 5—ordinarily termed the "waste" pipe—being adapted to receive the water when it is desired to cut off the same from the cistern.

Supported in the casing 2 above the mouth of the outlet 4, is an inclined filter screen 6, which, in accordance with a preferred form of my invention, is arranged with its upper portion 6' in a substantially 60 vertical plane, or in one only slightly inclined to the vertical, and with its lower portion 6" extending at a reducing angle 65 of inclination to a point above the waste outlet 5.

For directing the water received into the casing from the inlet 3, outwardly through either of the outlets, a spout 7 is supported beneath said inlet and is adjustable to direct the flow of the water through either of the 70 outlets as desired. Said spout 7, as here shown, is attached to the lower end of a pipe section or sleeve 8 which is rotatably and removably supported in the inlet pipe by means of an annular rib or collar 9 thereon 75 resting upon the upper end of said inlet pipe, as shown in Fig. 2.

The spout 7, when turned or adjusted to its normal position for directing the water through the screened outlet 4, as indicated 80 by broken lines in Fig. 1, is disposed at an angle oppositely inclined to that of the screen and with its discharge end opposite and adjacent to the upper portion of said screen, as shown. With this relative arrangement of the screen and spout, the water will be discharged from the spout in a concentrated volume against the screen, and this, in view of the angle of inclination of the opposed screen, will prevent any accumulation of the floatings in the water on the screen such as might tend to choke up or clog the latter, such floatings being washed downward over the face of the screen to the waste outlet 5.

To facilitate the ready passage of the floatings downward over the screen, the latter is preferably formed of smooth-surfaced sheet material having perforations therein, here shown in the form of elongated slots 110 arranged in staggered relation. The relatively smooth surface presented by such a

screen facilitates the passage of the floatings over it to the waste outlet, whereas the wire mesh material ordinarily used has a tendency to catch and hold the floatings. 5 Also, as a means to further concentrate the volume of water discharged from the spout against the screen, the end of the spout is made somewhat restricted in width as shown in Fig. 2.

10 When it is desired for any reason to cut off the flow of water to the cistern, the spout 7 will be turned or adjusted to direct the flow of water through the outlet 5, as indicated by dotted lines in Fig. 1. As a means 15 to accomplish this, the rib or collar 9 on the spout-carrying sleeve 8 is provided with a thumb-plate 11 which may be conveniently grasped by hand for turning said sleeve within the supporting inlet pipe 3. This 20 thumb-plate 11, as here shown, is positioned centrally above the discharge end of the spout and therefore also serves as a means for indicating the position of the spout within the casing relative to the outlet open- 25 ings.

To provide ready and convenient access to the interior of the casing for cleaning the screen or any other purposes, the casing is provided with a cut out portion in a position opposite the screen which is normally closed by a hinged cover 12. 30

The filter may be supported in position for use in any desired manner, the same as here shown being provided with hooks 14, 35 14, at opposite sides thereof for detachably

fastening the filter to a building or other desired support.

What I claim is:

1. A filter, comprising a casing having an inlet and a plurality of outlets, a filter screen 40 located over one of said outlets in an inclined position, and a spout located beneath the inlet in a normal position oppositely inclined to the filter screen and discharging directly against the same, said spout being 45 rotatable on a substantially vertical axis for movement to a discharging position over either of said outlets.

2. A filter, comprising an inlet pipe and a plurality of outlets, a filter screen located 50 over one of said outlets, a sleeve rotatably fitted in said inlet pipe and provided with a projection resting on the upper edge of the latter to removably support the sleeve in the inlet pipe, said sleeve carrying at its lower 55 end a spout which is shiftable by a turning movement of the sleeve to a discharging position over either of said outlets, and a thumb-plate fixed to the sleeve exterior of the casing as a means for turning the same 60 and also for indicating the position of the attached spout relative to the outlets.

Signed at Tiffin, in the county of Seneca and State of Ohio, this 22nd day of April, A. D. 1916.

CASPER THEODOR BUCHER.
